Primary Examiner—Jeffrey Asch

(74) Attorney, Agent, or Firm—Banner & Witcoff, Ltd.

(57) **CLAIM**

The ornamental design for a front cover for a handset, as shown and described.

DESCRIPTION

FIG. 1 is a bottom plan view of a front cover for a handset showing my new design;

FIG. 2 is a right side view thereof;

FIG. 3 is a front view thereof;

FIG. 4 is a left side view thereof;

FIG. 5 is a top plan view thereof;

FIG. 6 is a perspective front view thereof; and,

FIG. 7 is a bottom plan view of a second embodiment of the front cover for a handset of FIG. 1;

FIG. 8 is a right side view of the front cover for a handset of FIG. 7;

FIG. 9 is a front view of the front cover for a handset of FIG. 7;

FIG. 10 is a left side view of the front cover for a handset of FIG. 7;

FIG. 11 is a top plan view of the front cover for a handset of FIG. 7; and,

FIG. 12 is a front perspective view of the front cover for a handset of FIG. 7.
